CLAIM

The ornamental design for an bump cap inner shell, as shown and described.

DESCRIPTION

FIG. 1 is a top perspective view of an bump cap inner shell, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 3; and,

FIG. 11 is a partial enlarged view of FIG. 4.

The broken lines in the figures are for the purposes of illustrating portions of the bump cap inner shell, which form no part of the claimed design.

1 Claim, 8 Drawing Sheets
